COLLAPSIBLE COT

Mac Levine, Brooklyn, N. Y.

Application May 15, 1933, Serial No. 671,046

1 Claim. (Cl. 5—111)

The subject of this invention is a collapsible cot which among other advantages comprises but few repeatedly used standard parts and is hence inexpensive to manufacture; whose bottom is made up of coil springs like those used in the bottom of a comfortable, regular bed; which can be collapsed to occupy a small compass so that it can be easily and inconspicuously stowed away in a closet or in a corner when not in use; which is comparatively light and easy to handle; which can be collapsed and opened up quickly and with but a minimum of exertion; and which is sturdy and neat of appearance.

15. Generally stated, the cot of the present invention consists of a pair of frame sections of substantially equal length pivotally tied together, each frame section having associated therewith a coil spring bottom and a pair of collapsible legs, the construction and arrangement of the sections being such that they can be readily folded over each other with the coil springs of one section fitting in the spaces between the coil springs of the other and the legs of the two sections collapsible to positions in between the sections.

25 With the foregoing and other features and objects in view, my invention will now be described with particular reference to the accompanying drawing, wherein.—

Figure 1 represents a side view of a collapsible cot embodying the present invention in both open and collapsed positions, the collapsed position being indicated by dotted lines, and, for the sake of clarity, being shown without the bottom coil springs.

25 Figure 2 is a plan view of the cot.

55 Figure 3 constitutes a section on the line 3—3 of Figure 1.

Figure 4 illustrates a side view of the cot in collapsed condition.

40 The frame-work of the cot, including its legs, can be built up from any suitable or standard bar stock, that shown being angle iron which affords the desired sturdiness at low expense. As already indicated, the cot is made up of a pair of frame sections indicated generally at 1 and 2. The sec-
45 tions are of substantially the same width, but the

tions are of substantially equal length and together define a bottom frame which, as appears in Figure 2, is of substantially rectangular form. At the inner ends of the longitudinal bars 3, 3 and 4, 4 of each section are short tie or bridge pieces 5 to which such ends are pivotally secured, thereby rendering the sections collapsible from their normal tandem relationship to a collapsed and parallel side-by-side relationship, as depicted in Figure 1.

Each of the sections is provided with a pair of legs 6 which are pivotally secured to the bottom frame adjacent to its outer ends and which can be collapsed upon the collapse of the cot so as to lie in between the collapsed sections in substantial parallelism therewith, as appears in Figure 1. These legs are preferably associated with means automatically operable upon the collapse of the cot to collapse them also. Such means as shown takes the form of a link 7 for each leg, each link being pivotally secured at its inner end to the corresponding piece 5 and at its outer end to the upper end of the corresponding leg 6. Each link extends longitudinally alongside of the corresponding longitudinal bar and lies immediately next to it so that danger of bending or otherwise injuring the link is minimized. It is plain that the links are adapted to act automatically upon the collapse of the sections to collapse the legs in between the collapsed sections in substantial parallelism therewith, as previously explained. In order to stop the pivotal movement of the legs when the sections are in normal, tandem relationship, the legs may have stopping lugs 8 thereon adapted to abut against the longitudinal bars when the sections are in this relationship. It is preferable that such stoppage occur with the legs of the two sections inclined to diverge somewhat from each other, as shown in Figure 1, so that there may be no tendency for collapse of the cot to take place while it is in use.

The bottom of the cot is afforded by coil springs 35 suitably supported and tied together to permit of collapse into a small compass, as previously stated. To this end, spaced U-shaped bars 9 are suspended from and span perpendicularly the longitudinal bars of each section, as best shown in Figure 3, to which they may be riveted, welded, or otherwise suitably secured. Each bar serves as a truss or support for a row of coil springs 40 10 whose lower ends may be threaded therethrough and headed thereover or otherwise suitably fastened thereto. The spanning portion of each bar is preferably of U-section so as to provide the desired rigidity and strength. 45

The upper ends of the springs are tied together to suitable framework in any approved manner. As shown, groups of four springs are tied together at their upper ends by crossed, interlocking helical tie wires 11 as is well known in the art. The border springs in each section may be fastened at their upper ends, as by clips 12, to a U-shaped, wire frame 13. The center pieces 5 may also have suspended therefrom a central U-shaped bar 14, like the others 9, car-

rying a central row of coil springs whose upper ends are clipped to a rectangular wire frame 15, with the ends 13a of the U-shaped frames 13 being bent loosely about the frame 15 so as to permit collapse of the frame sections. The frame sections 3 and 4, the wire frames 13 and the frame 15, and the upper ends of all the coil springs lie substantially in a single plane to afford the bed bottom as a whole. It is thus seen that when the cot is collapsed, the wire framework is continuous in the sense that it does not show a break or division. The spacing or arrangement of the bars and coil springs in the two sections is such that with the sections collapsed to a parallel side-by-side relationship, as illustrated in Figure 4, the bars and springs and the horizontal cross braces for the legs in one section are received in the spaces between the bars and springs in the other section. This means that the end row of springs in the section 3 will have to be spaced from the end of the wire frame 13. It is hence advantageous to fill in this space or gap by an arched reinforcing wire 16 whose ends are clipped to the end of the wire frame 13 and whose arched portion is clipped to the upper ends of the intermediate coil springs in the end row.

It is further desirable to provide legs at the center of the cot, which legs may assume the form of a U-shaped bar 170 whose upper ends are rigidly secured to the pieces 5 and whose base portion lies in the same plane with the lower ends of the legs 6 when the cot is opened as shown in Figure 1. This central support for the cot serves to keep it from tending to sag centrally even when subjected to rugged service or put to an undue stress on the legs 6. The central support extends in between the sections

when they are in collapsed, parallel side-by-side relationship, as illustrated in Figure 4. Suitable means for locking the two sections in collapsed relationship may be provided, as in the form of a hook 17 in swivelled engagement with one of the frame sections and adapted to engage a pin or catch 18 on the other section. 5

I claim:—

A collapsible cot comprising a pair of frame sections of substantially equal length forming as 10 a whole a substantially rectangular frame, pieces bridging the inner ends of the longitudinal bars of said sections and to which said ends are pivotally secured so as to render said sections collapsible from their normal tandem relationship 15 to a side-by-side relationship, spaced U-shaped bars suspended from and transversely spanning the longitudinal bars of each section, and rows of coil springs supported at their lower ends by said bars and tied together at their upper ends 20 to form the cot bottom, the arrangement of said bars and springs in the two sections being such that with the sections collapsed to a parallel side-by-side relationship the bars and springs in one section are received in the spaces between 25 the bars and springs in the other section, said cot further including a U-shaped bar suspended from and spanning said pieces, a central row of coil springs supported at their lower ends by said bar, U-shaped frames to which the upper 30 ends of border springs of each section are secured, and a rectangular wire frame to which the upper ends of said central row of said coil springs are secured, the ends of said U-shaped frames being loosely bent about said rectangular frame to permit the collapse of said sections. 35
